UNITED STATES PATENT OFFICE.

HENRY C. MILLER, OF WATERFORD, NEW YORK.

LOADER FOR BUTTONHOLE-MACHINES.

1,300,446.

Specification of Letters Patent. Patented Apr. 15, 1919.

Application filed January 31, 1918. Serial No. 214,654.

To all whom it may concern:

Be it known that I, HENRY C. MILLER, a citizen of the United States of America, residing at Waterford, in the county of Saratoga and State of New York, have invented 5 certain new and useful Improvements in Loaders for Buttonhole-Machines, of which the following is a specification.

This invention relates to improvements 10 in machines for locating buttonholes in collars, better known in the art as loaders for buttonhole machines.

Heretofore loaders for this purpose have been mounted to slide horizontally toward 15 the buttonhole machines, such for instance as disclosed in my prior Patents Nos. 793,066, June 20, 1905, and 793,010, June 20, 1905.

In my present construction the loader is 20 mounted to rock on a pivot and moves in an arcuate path toward and from the buttonhole machines, the parts being so arranged that the edge of the loader in its delivery movement snugly engages the base of each 25 buttonhole machine, which insures of collar tabs being placed snugly under the work clamp.

Therefore, one of the objects of my present invention is to provide in a pivoted 30 loader, means which will enable the operator to quickly gage and insure of a collar being held in gaged position and introduced under the work clamp of the buttonhole machine.

A further object of the invention is to 35 provide a loader with means for gaging a collar of any size and angle, and insure of the collar tabs being rigidly and smoothly held in position while being introduced under the work clamps.

40 A still further object of the invention is to provide safety means which will prevent the operator forcing the loader with the gage collar thereon against the work clamps, if the latter have not been previously lifted 45 by the operator.

The invention also comprehends improvements in the details of construction and arrangement of parts which will be herein-after described and particularly pointed out 50 in the claims.

In the drawings:—

Figure 1 is a perspective view of the loader applied, the buttonhole machines being but conventionally illustrated.

Fig. 2 is a side elevation, the end buttonhole machine being removed, to illustrate the work clamp and associated parts of the machine on the opposite side.

Fig. 3 is an enlarged detail plan view of the loader in its normal position.

Fig. 4 is an enlarged side elevation of the loader in its normal position, the breaker bar and fingers being elevated in dotted lines.

Fig. 5 is a similar view, but showing the loader in position when delivering a gaged collar to the buttonhole machines.

Fig. 6 is a plan view of the loader, the dotted lines indicating its position when delivering a gaged collar to the buttonhole machines.

Fig. 7 is a detail perspective view of the lock for the loader.

Fig. 8 is a view of the end of the gage.

Fig. 9 is a detail section taken through the work clamp after the latter is lowered to engage a collar and the platform.

The buttonhole machines 1—1 are but conventionally illustrated in the accompanying drawings, and for the detail description and disclosure of same, if necessary, reference may be made to my companion application, filed Sept. 15, 1917, No. 191,573. While it is not absolutely essential that the buttonhole machine referred to be employed in connection with the present invention, yet there are connections to be described which are particularly adapted to a machine such as shown. 2 indicates a table, supported on a frame 3. Mounted on the top of the table 2, in spaced relation, are the buttonhole machines 1—1, each including a base 5, a work clamp 7, a needle bar 8, and stop mechanism 9.

A bracket 12, extends from the front of the table, and on a pin 13 at the outer end of this bracket is pivoted a frame 14, of approximately S shape in side view. A casting 15 is pivotally mounted on a pin 16, supported on the upper end of the frame 14, and this casting is secured to a platform 17, and from the rear of said casting projects a rod 18.

On the upper edges of the platform are two fixed bars 19—19, and mounted in same near the forward ends is a shaft 20. Adjustable in the shaft 20, and projecting rearwardly therefrom outside the side bars, are

two rods 21—21, the rear ends of said rods are bent inwardly toward each other, and are then again bent rearwardly, and each is provided with a resilient smoothing finger 22. These fingers normally fit in slots 23, formed in the rear edge of the platform, and they are formed of thin resilient wire to hold the collar tab flat, and to gently engage said tabs when a collar is gaged.

10 On the inside of the rear end of each side bar 19, is a block 24, and adjustably mounted therein by set screws 25, are seam gages 26. Each seam gage comprises a stout wire, bent upwardly at 28, and downwardly and forwardly at 29, and thence downwardly and rearwardly at 30. The purpose of so bending the gages is to form arches to allow ample room for the operator's hands when gaging a collar on the platform, as will appear later on.

Extending upwardly from the shaft 20, is a breaker rod 32, which is bent downwardly and rearwardly toward the rear of the platform, the lower end resting on or close to the surface of the platform, and between the two seam gages. A spring 33 is attached to the vertical portion of the breaker bar, and its rear end is attached to a stud extending upwardly from the rod 18. Located on the top of the platform are two adjustable tab gages 17^a—17^a. Each tab gage is cut at an angle on its rear edge, and is also provided with a slight flange 17^b, the inner rear pointed end of each gage fitting in the tab crotch of a collar when gaging the latter. Each gage is provided with a slot 17^c through which a set screw 17^d passes to adjustably hold the gage in set position.

40 A standard 34 extends from the rear of the table, and it is provided with an opening 35, through which the rod 18 passes. The opening 35, is somewhat larger than the diameter of the rod to permit free movement of the latter when the loader is moved toward and from the buttonhole machines. On the rear end of the rod 18, is a buffer 37. Located some distance forward of the buffer 37 is a collar 38, and on the rear face thereof is a buffer 39. The buffer 39 abuts against the front of the standard 34, when the loader is forced rearwardly, while the buffer 37 abuts against the rear face of the standard when the loader is returned to normal position, the buffers of course being for the purpose of reducing shocks.

45 A spring 40, is connected at its forward end to the frame 14, and at its rear end it is attached to the standard 34, the tension of the spring being to move the loader toward the buttonhole machines.

50 A bracket 41 is bolted to the base of the standard 34, and it is provided with two pivot pins 42, on which are pivoted two arms 43, each having a semi-circular head 44, at its upper end, the inner edge of each

head having a notch 45, and when said heads are brought together, they embrace the rod adjacent the front abutting surface of the standard 34. A spring 46 connected to pins projecting from the arms, serves to normally bring the heads together, and when in this position they form an abutment or stop for the buffer 39, and limit the rearward movement of the loader.

55 The arms 43 of course are adapted to be opened against the tension of the spring 46, and the loader returned to normal position against the tension of the spring 40, by manual means, which will be described later on.

Extending forwardly from the buttonhole machines are guides 45^a, the forward ends of which incline downwardly. When the loader is pushed rearwardly to deliver a gaged collar to the buttonhole machines, the rear edge engages guides to guide the platform in its travel toward the work clamps.

60 On the rear inner portion of each base of the buttonhole machines is a bracket 46^a, and in each bracket is adjustably mounted a forwardly extended finger 47^a, the free ends of the fingers being bent upwardly. As shown, on each finger is a gage or stop 47^x against which the rear edge of the collar abuts when in position to be clamped. These fingers are disposed beyond the path of travel of the breaker rod, and serve to prevent the central folded or slack portion of the gaged collar falling over on the work clamps, after the loader has delivered the collar to the button-hole machines.

65 Mounted in the lower part of the frame 3, is a shaft 50, and extending therefrom is an arm 51, pivotally connected by a link 52, with a foot lever 53, pivoted on a bracket 54^{xx}, attached to the front edge of the table 2. A lever 54^a is fixed to the shaft 50, and to the rear end thereof is secured a chain 54^x attached to a spring 55, and fastened to the other end of the spring are the lower ends of two diverging chains 56—56. The chains 56 are attached to the upper ends of arms 57, mounted on shafts 58, which when turned in one direction rocks the shaft 58, and lifts the work clamps. Chains 61, connect the arms 43, with the lower ends of the levers 57, so that at the time the work clamps 7—7 are raised, the arms 43, will be rocked apart to remove the heads 44, from the path of the buffer 39, to permit the inner end of the loader to pass under the work clamps. Secured to the forward end of the lever 54^a, is a chain 59^a, which is trailed over a pulley 60, on the standard 34, and is fastened at its outer end to the collar 36. This connection is for the purpose of ejecting the loader from under the lowered work clamps, just prior to the starting of the buttonhole machines. To the lower ends of the levers 57, are attached chains 59, the inner ends of the latter being 130

secured to a spring 59^a and to the bottom of the spring is fastened a chain 59^b, which is attached to the forward end of the lever 54^a, the purpose of this connection being to 50 inversely rock the shafts 58, to start the buttonhole machines, and operate the trimmers, etc.

Let it be assumed that the parts are in the position shown in Fig. 1, that is, the loader 10 is in its normal position ready to receive a collar, and the work clamps on the button-hole machines are down. The operator depresses a treadle 70, which is connected by a chain with a lever 71, fast on the shaft 20, 15 which rocks said shaft and elevates the smoothing fingers 22, and the breaker bar 32, to the position shown in dotted lines in Fig. 4. The operator now grasps with two hands, the opposite ends of a collar, and lays 20 it over the breaker bar, holding the tab ends on the platform and at the same time pushes the collar rearwardly until the tab crotches 25 a snugly engage the tab gages 17^a, as shown in dotted lines in Fig. 3. While gaging the tabs with the tab gages, the seam 6, of the collar is gaged by the ends of the seam gages 26, which of course, like the tab gages, have been set to locate the collar in the proper 30 position to form the buttonholes in the tabs when the collar is moved under the work clamps.

After the collar has been properly gaged, pressure on the treadle 70 is removed, and the spring 33, lowers the smoothing fingers 35 and the breaker bar, the fingers bearing gently on the inner ends of the tabs to temporarily hold them down, while the breaker bar assumes its normal position on the platform. By this means the collar is practically held clamped to the platform in position against the seam and tab gages, and is now ready to be delivered to the buttonhole machines.

When gaging the collar no attempt is 45 made to stretch it; on the contrary the ends are drawn together by the operator, and the breaker bar, consequently a central loop or fold *c*, is formed in the center of the collar, between the two seam gages.

The operator now rocks the foot lever 53, 50 rearwardly from its neutral position shown in full lines at A in Fig. 2 to the dotted line position B, which, through the lever 54^a, and the chains 56, rocks the shafts 58, and 55 through connections not specifically described, elevates the work clamps 7—7, and simultaneously through the chains 61, spreads the arms 43, and opens the heads 44. At about the same time the loader is pushed 60 rearwardly on the pivot 13, the rear edge of the platform engages and rides up on the guides 45^a. Immediately the spring 40 overcomes the weight of the loader, due to 65 the upper end of the frame 14 overhanging the front of the pivot 13, the spring acts to

carry the loader under the work clamps of the buttonhole machines, which, as previously stated, are now elevated. The buffer 39, abuts against the standard 34, and limits the movement of the loader, the buffer having been previously adjusted so that the tabs of the collar will lie in proper position under the work clamps to receive the buttonholes. The operator now rocks the foot lever toward the front of the machine to its 70 neutral position and the work clamps are lowered on the collar tabs, the light resilient fingers being slightly pressed into the fabric by this action, but not enough to distort the tab, the slots 23 assisting in this function. 75 This movement also slackens the chains 61, and the spring 46 returns the arms 43 to permit the heads to assume normal position when the loader is withdrawn.

Further movement of the foot lever 53, 80 toward the front of the machine past its neutral position, as shown in dotted lines at C, which will cause the front end of the lever 54^a to pull on the chain 59^a, and promptly withdraw the loader from under 85 the work clamps 7, whereupon the operator quickly restores the loader to its normal position. The loader having been withdrawn from the clamps, further continued movement of the foot lever 53, causes the front 90 end of the lever 54^a to pull on the chains 59 which rocks the shafts 58 in the opposite direction, and through mechanism not 95 specifically shown, the buttonhole mechanism is started, and when the buttonholes 100 are finished, the usual automatic means stops the operation. When the loader is withdrawn against the tension of the spring 40, through the mechanism described, immediately the platform and associated parts 105 pass over the vertical center of the pivot the weight will overbalance the spring and the loader moves from the rails and settles to normal position, the buffer 37 abuts against the standard 34, and absorbs the shock, and 110 at the same time limits the return movement of the parts. While this movement is taking place, the operator has another collar in hand ready to gage it for the next operation.

When the loader is pushed in to locate the tabs under the work clamps, the fingers 47^a act to prevent the loop or fold in the slack portion of the collar falling on either of the clamps, while the rear edge of the collar engages the gages 47^x.

If, when the operator pushed the loader in, he neglected to raise the work clamps, the heads 44, on the arms 43, acts as a lockout and be interposed in the path of the buffer 125 39. The heads 44, form an abutment for the buffer 39, and the loader is locked against further movement, hence the rear edge of the platform is prevented from contacting with the front edges of the clamps, and 130

damage to the parts and dislocation of the gaged collar is avoided. When this occurs, it serves as a warning to the operator that something is wrong, as the parts are arranged to preclude accidents which follow from negligence of this character.

When the loader and the rod 18, rock to deliver a gaged collar, it swings substantially on an arc, the opening in the standard 10 permitting of the rod having this movement.

This action causes the rear edge of the platform to bear snugly on the rails, which insures of the collar being fitted closely under the clamps.

15. By the construction described, the mechanism is protected against damage, and the collar is accurately gaged and is positively held in gaged position to properly locate the buttonholes. Furthermore, the construction 20 is such that fewer parts are employed and therefore economy in up-keep is greatly reduced.

While the collar is gaged and introduced to the buttonhole machines manually, the 25 operation of forming the buttonholes is all automatically performed, and as previously stated, one operation is dependent on another.

Of course, the gages are set to accommodate 30 collars of different styles, as the seam line and the tabs of collars vary, and it is to accomplish this purpose that the gages are made adjustable.

So far as I am aware, it is new in the art 35 to gage all sizes of collars as described in this application, it having heretofore been thought necessary to stretch the collar, or flatten it out lengthwise on the platform to gage it for properly locating the buttonholes in the tabs.

40. What I claim is:—

1. In combination a buttonhole machine, a platform, gages on the platform to gage a collar preparatory to forming a buttonhole therein, means for pivotally mounting the platform, and means permitting reciprocal movement of the platform toward and from the buttonhole machine.

2. In combination, a buttonhole machine, 50 a pivoted reciprocal loader having gages to gage a collar previous to its introduction to the buttonhole machine, and means to permit of movement of the loader toward and from the buttonhole machine.

55. 3. In combination, a buttonhole machine, a loader having gages to gage a collar previous to its introduction to the buttonhole machine, means for mounting the loader to cause it to travel in an arcuate path toward 60 and from the buttonhole machine, and means to permit reciprocal movement of the loader toward and from the buttonhole machine.

4. In combination with a pair of buttonhole machines, a loader common to both buttonhole machines and comprising a pair of

gages to engage opposite end portions of a collar, means for holding the collar in gaged position on the loader, means for raising the holding means, and means for pivotally and reciprocally mounting the loader to permit 70 of same moving toward and from the buttonhole machines in an arcuate path.

5. In combination, buttonhole machines, a loader comprising a platform, tab gages thereon, seam gages on the platform, pivotally mounted tab holding devices, means for operating the latter, and means for pivotally mounting the loader to permit same to be moved toward and from the buttonhole machines in an arcuate path. 80

6. In combination, buttonhole machines, a loader comprising a platform, tab gages on the platform, a breaker bar between the tab gages, smoothing fingers engaging the collar tabs, means for pivotally mounting the breaker bar and the smoothing fingers, and means for mounting the loader to permit movement of the same toward and from the buttonhole machines. 85

7. In combination, buttonhole machines including clamps, a loader including gages, means for pivotally mounting the loader to cause same to move in an arcuate path toward and from the buttonhole machines, a guide rod extending from the rear of the loader, a loose bearing on the rod, buffers to absorb the shock of the loader, and means with which the rod co-operates for preventing the loader delivering a collar to the buttonhole machines until the clamps are elevated. 90

8. In combination, a buttonhole machine including a clamp, means for raising the clamps, a loader movable toward and from the buttonhole machine, a stop for preventing the loader introducing a collar to the buttonhole machine until the clamps are elevated, and connecting means between the stop and the clamp operating means to remove said stop at the time the clamp is elevated. 100

9. In combination, buttonhole machines including clamps, means for operating the clamps, a loader common to said machines and provided with collar gaging and positioning means, means for limiting the movement of the loader in two directions, a stop to prevent movement of the loader against the clamps when the latter are down, and means connecting the stop and clamp operating means to remove said stop at the time of elevation of the clamps. 115

10. In combination, a pair of buttonhole machines, a loader movable toward and from said buttonhole machines and adapted to hold a collar with its two ends smoothed and gaged, comprising tab gages, seam gages, a breaker bar interposed between said gages, means for holding the tabs and part of the seam of the collar when gaged, means for 125

delivering the positioned collar to the buttonhole machines in clamped sewing position, and means for withdrawing the loader from under the collar and starting the stitching mechanism.

11. In combination, a pair of buttonhole machines, a loader including means for gagging and holding the tabs of a collar whose central portion is slack, means permitting 10 of the moving of the loader toward and away from the buttonhole machines, and forwardly projecting fingers adjacent the buttonhole machines to overlie the collar and prevent the slack portion of the gaged collar falling toward said machines during the period of formation of the buttonholes.

12. In combination, a buttonhole machine, a loader comprising a platform, tab gages thereon, a pivoted breaker bar between the 20 tab gages, means engaging the tabs after being gaged, means for raising the breaker bar to support the body of the collar while being gaged, means for moving the loader toward and from the buttonhole machine.

13. In combination, a pair of buttonhole machines including work clamps, a loader comprising a platform formed in its rear edge with notches, tab smoothing fingers in alinement with the work clamps and cooperating with the notches, means for elevating the smoothing fingers, adjustable tab gages, on the platform adjacent the notches, seam gages on the platform, and means for moving the loader toward and from the buttonhole machines the clamps pressing on the smoothing fingers when lowered to hold the tabs of the collar in gaged position when the loader is withdrawn.

14. In combination, a pair of buttonhole machines, a pivoted loader movable in an arcuate path toward and from the buttonhole machines, the loader having a pair of seam gages adjustably supported from the outer edges of the loader, the said loader also having end gages for gaging a collar, and means for guiding the loader and limiting its movement toward the buttonhole machines.

15. In combination, a pair of buttonhole machines, a loader comprising a platform a pair of adjustable tab gages, a pair of resilient arched seam gages adjustably mounted near the sides of the platform and having their ends disposed between the tab gages, a breaker bar located between the seam gages, resilient smoothing fingers located adjacent the tab gages, means for simultaneously raising and lowering the smoothing fingers and the breaker bar, and means for limiting the movement of the loader in gaging position.

16. In combination, a pair of buttonhole machines, including work clamps, a loader, means thereon for gaging a slack collar and holding the tabs in gaged position, a rod ex-

tending from the loader, buffers on the rod, a standard having stops with which the buffers abut to stop the movement of the loader when the work clamps are down, means for simultaneously elevating the clamps and 70 removing the stop, and means for moving the loader toward the clamps.

17. In combination, a pair of buttonhole machines, a loader comprising a platform having collar gages thereon, a frame for 75 pivotally supporting the loader the upper portion of said frame overhanging the lower portion when the loader is in its normal position to throw the weight of the loader in front of its pivot, a spring for moving the 80 loader toward the buttonhole machines after the weight has been thrown rearwardly of the pivoted point, and manual means for withdrawing the loader to normal position.

18. In combination, a pair of buttonhole 85 machines, a loader including collar gages, a spring for moving the loader toward the buttonhole machines, and means for pivotally mounting the loader to cause its weight to hold said loader in normal position 90 against the tension of the spring, whereby manual movement of said loader to overcome the weight is necessary before the spring acts to move it in operative position.

19. In combination, a pair of buttonhole 95 machines including work clamps and starting means, a control lever, connections between the control lever and the starting means, connections between the control lever and the work clamps, a loader comprising a 100 platform having collar gages thereon, means for moving the loader toward the buttonhole machines, a stop for preventing the loader contacting with the work clamps when the latter are down, means connecting the stop 105 with the work clamps to cause both elements to be simultaneously operated by the control lever, and means connecting the loader to withdraw same by the control lever prior to the latter actuating the starting means.

20. In combination, a pair of buttonhole machines, a loader comprising collar tab gages, and means to hold a slack collar in gaged position, the said means comprising 115 tab holding fingers and seam gaging elements, means for operating the loader toward and from the buttonhole machines, and means for limiting the movement of the loader toward the buttonhole machines. 120

21. In combination, a pair of buttonhole machines, a loader comprising a platform having collar tab gages, a pivoted supporting frame, said loader being pivotally mounted to the pivoted supporting frame, a 125 standard having a guide therein, a rod fixed to the loader and freely movable in the guide, and buffers on the rod which abut against the standard to limit the movement of the loader in both directions. 130

22. In combination, a pair of buttonhole machines, having work clamps, starting mechanism, a loader movable toward and from the buttonhole machines to deliver a gaged collar under the work clamps, a frame, supporting the buttonhole machines and the loader, manual means for operating the loader to deliver a gaged collar under the work clamps, a foot lever pivotally mounted at its upper end to the frame and normally in a neutral position, connections between the foot lever, the work clamps, the loader and the starting mechanism, the foot lever when moved in one direction causing the lifting of the clamps and in returning to neutral position permitting of the clamps being lowered and clamping the collar and the loader, movement of said foot lever past the neutral position in the opposite direction withdrawing the loader from under the clamps and upon further movement in the same direction starting the buttonhole machines.
23. In combination, buttonhole machines having work clamps, means for raising the work clamps, a loader, means for withdrawing the loader from under the work clamps, loader lockout means, starting mechanism, means for actuating the starting mechanism, and a single element for operating the clamp raising means, the loader withdrawing means, actuating the lockout means, and operating the starter actuating means.
24. In combination, a pair of buttonhole machines having work clamps, means for raising the clamps, a loader, a lock for the loader, starting mechanism, an operating element normally in a neutral position, means connecting the operating element and the clamp raising means and the loader and the loader lock and the starting mechanism, whereby when the operating element is moved rearwardly from neutral position the work clamps will be raised and the lock released, and when said element is returned to neutral position the clamps are lowered on the collar and continued movement past the neutral position withdraws the loader from under the clamps and the starting mechanism is actuated.
25. In combination, a buttonhole machine, having a clamp, a loader movable toward and from the buttonhole machine, said loader having a slot at its inner end, a smoothing device located over the slot, means for operating the loader to present a collar and the smoothing device under the clamp, and means for raising and lowering the clamp, the latter when lowered gently pressing on the smoothing device and forcing the fabric thereunder into the slot, the pressure being such as to permit withdrawal of the loader from under the collar and leave the latter in clamped position.
26. In combination, a pair of buttonhole machines, a loader, gaging devices carried by the loader to gage the tabs of a collar the central portion of the collar when gaged being free and loose, means for holding the tabs in gaged position, and means for preventing the loose portion of the collar falling toward the gaged tabs.
27. In combination, a pair of buttonhole machines, a reciprocal and pivoted loader, gages on the loader to gage the ends of the article operated upon the article being free and loose between its gaged ends, means for holding the gaged ends of the article, and means for preventing the loose portion of the article falling toward the gaged ends.
28. In combination, a pair of buttonhole machines, a loader, and means on the loader for gaging and holding the ends of an article which is loosely sustained between the gaged ends, and means permitting movement of the loader to introduce the article to the buttonhole machines and permitting operation of the stitching mechanism while the article is loosely sustained.
29. In combination, a pair of buttonhole machines to operate on the opposite ends of an article and spaced apart a less distance than the length of the article, and reciprocal means to introduce a gaged article to the buttonhole machines and stitch same while the intermediate portion of said article is loosely sustained.
30. In combination, stitching mechanism, a reciprocal and pivoted loader, gages on the loader to gage the ends of the article operated upon, and means for holding the gaged ends of the article.
31. In combination, stitching mechanism, a reciprocal and pivoted loader, gages on the loader to gage the ends of the article operated upon, a clamp adjacent the stitching mechanism, means for raising the clamp, means for starting the stitching mechanism, and manually operating mechanism for first operating the clamp raising means, subsequently withdrawing the loader from under the clamp and finally actuating the starting means.
32. In combination, a pair of buttonhole machines, including clamps, a reciprocal loader, gages on the loader, means to lower the clamps on the gaged article and the loader, and manual means to subsequently force the loader from under the clamps and later by manual operation start the stitching mechanisms.
33. In combination, a pair of buttonhole machines, a reciprocal loader to introduce articles to the buttonhole machines, arch shaped devices supported on the loader and provided at their inner ends with smoothing devices, and a movable breaker bar between the arch shaped devices, whereby the center of an article to be gaged is supported by the breaker bar, and the arch formation per-

mits of the passage of the hands of the operator in placing the ends of the article under the smoothing devices.

34. In combination, a pair of buttonhole machines, a reciprocal loader, means for mounting the loader to require manual operation to move it a part of the way toward the buttonhole machines, and means for automatically completing the movement of the 10 loader toward said buttonhole machines.

35. In combination, a pair of buttonhole machines, a reciprocal loader, means for mounting the loader to require manual operation to move it a part of the way toward 15 the buttonhole machines, means for automatically completing the movement of the loader toward said buttonhole machines, and means for withdrawing the loader from the buttonhole machines.

20 36. In a buttonhole machine, the combination of stitching mechanism, automatic

stopping and starting mechanism, power operating means, a work clamp, mechanism for raising the work clamp including means having three positions by which the clamp 25 is manually raised when the mechanism is moved in one direction to one of said positions the work clamp being in clamping engagement with the material when the said means is in another of the three positions, 30 and when said means is moved to the third of the three positions, the automatic starting mechanism is thrown into coöperation with the power operating means to operate the stitching mechanism. 35

In testimony whereof I affix my signature in the presence of two witnesses.

HENRY C. MILLER.

Witnesses:

JOHN SINNOTT,
ELEANOR F. JELF.
